FRITZ FALLERT, OF BERN, SWITZERLAND

PRINTING PRESS

Application filed March 24, 1931, Serial No. 524,834, and in Germany June 29, 1928.

Printing presses for printing both sides of the paper web are known, in which two vertical formes are employed mounted in fixed opposite positions and coacting with corresponding impression cylinders which are mounted in common slides adapted to be moved up and down.

This invention relates to a device on such presses which effects the intermittent rotation of the perfecting cylinder mounted in the slides, the inking rollers of which are mounted in the same slides, the stroke of which for inking the entire forme must therefore be longer than the format of the matter to be printed and the corresponding peripheral dimensions of an impression cylinder.

In a known printing press of this construction, the driving pinions connected to the impression cylinders and actuated by racks mounted on the frame of the machine are gapped or flattened at the points corresponding to the channels on the impression cylinders, and therefore cannot gear with the racks at said points but merely slide over the latter. With this method of operating, the stopping and restarting of the rotary movement of the impression cylinders are effected by a special auxiliary drive.

The gaps or flattened portions of said pinions connected to the impression cylinders are bridged over by means of auxiliary toothed members which are provided beside said pinions and cooperate with positively controlled auxiliary racks, which are adapted to be swung into and out of the path of said toothed members. By means of this control device, the auxiliary toothed members in combination with the pinions proper operate in such a manner, that the printing cylinders, as soon as the cylinder slide during the drawing in of the paper web has performed a stroke corresponding to the height of the format of the matter to be printed, adjacent one of the dead point positions suddenly will start to rotate with a peripheral velocity corresponding to the speed of the slide and during the further movement towards the dead point and also during the return movement towards the other dead point will continue to rotate with a peripheral ve-

locity corresponding to the speed of the slide.

Since in the described control the impression cylinders are suddenly rotated from a standstill with a peripheral velocity corresponding to the speed of the slide without any intermediate stage, jolts which set up uneven running in the press and heavy material stresses, are liable to occur especially at high speeds.

The purpose of the invention is to enable the change from a standstill to the full peripheral velocity of the impression cylinders to proceed gradually. Accordingly the auxiliary racks are so arranged that they are able when brought into engagement to describe a movement in the direction of that of the slide and thus by gradually lowering their speed in relation to that of the slide set the impression cylinders revolving smoothly. It is true that a length of paper exceeding that of the format of the printed matter is at first drawn from the web, this excess is taken up again during the return of the slide, because these auxiliary racks also slip back until just before the impression begins, and the peripheral velocity of the impression cylinders is correspondingly reduced.

The invention will be clearly understood from the following description aided by the annexed drawings in which one typical embodiment of the invention as applied to a printing press having two vertically disposed and oppositely fixed printing formes, is illustrated and in which

Fig. 1 is a vertical section in partial side elevation of the control arrangement and the drive for the impression cylinders, the rack driving mechanism for the impression cylinders being shown on the left of the figure, and the new control on the right.

Fig. 2 is a partial elevation of the arrangement in Figure 1 and shows the control with the slide in position B.

Figure 3 is a partial vertical section through the inking gear mounted in slides, with a side elevation of the printing bed.

Figure 4 is a cross section on a larger scale, above the slide and partial section through the impression cylinders through

the representation according to Figure 1 in plan.

Figure 5 shows the arrangement of the control drive in cross section, through the 5 arrangement according to Figure 1 and in plan.

In the drawings Figure 1 represents as a typical embodiment a known printing press with two vertical printing formes opposite- 10 ly mounted in fixed position each of which coacts with a corresponding impression cylinder 1, the cylinders being mounted in a common slide 2 which is adapted to move up and down. The printing beds are hinged 15 in the press so as to open and close. The slide 2 is moved up and down by means of the crank wheels 3 and crank rods 4, arranged on each side of the press. The length of the format of the printed product is indicated by the letters A and B in Figures 1 and 3, whilst the letter C shows the end 20 position of the impression cylinders in the upper dead point. During the upward movement of the slide 2 from the dead point A to B, the impression cylinders remain stationary. At B the actuation of the cylinders begins and these revolve until they reach the upper dead point C. The distance thus traversed corresponds to the stroke necessary 25 to allow the roller 6, which inks the formes 5, to pass beyond the end of the latter.

During their downward travel from C to A, the impression cylinders 1 at first turn 30 back as far as B, into the position in which the centre of the channel is over the end of the format, and then describe their rotary or rolling movement over the formes. The positive actuation of each impression cylinder 35 1 is effected in known manner by means of pinions 7 which are mounted on the impression cylinders and gear with racks 8 (Figures 1 and 4), bolted on to the side members 10 which accommodate the fixed printing beds 9. As can be seen more particularly 40 on Figures 1 and 2, the pinions 7 are provided on that side which faces the channel side 11 of the impression cylinders, with flats 12 where the teeth are cut away so that 45 during the upward movement of the slide 2 when the impression cylinders must remain stationary the pinions 7 do not engage the racks 8 (Figures 2 and 3).

The impression cylinders 1 mounted in the 50 reciprocating slide 2 are provided with driving pinions 7, which are flattened at the parts facing the channels in the impression cylinders and can therefore slip over the racks 8 on the frame of the press, whereas they roll 55 over the racks when brought into engagement therewith. The slide is actuated by the pitman 4. In order to bridge over the gaps in the pinions 7, the impression cylinders are also provided with adjacently 60 mounted toothed-segment pinions 13, which

engage in the manner hereinafter described with the auxiliary racks 17, when the slide is in the top position and with the rack levers 15 when the slide is in bottom position.

In order to prevent accidental rotation 70 of the impression cylinders during the insertion of the paper web, each impression cylinder is provided with a special lever which is mounted on the slide 2 and one arm of which 18 engages in a groove on the pinion 13, by means of the roller 19, whilst the other arm 18a is guided by means of the roller 20 in a groove 21 in the lateral guide rod 22.

On their upper ends, the lateral guide rods 22 carry the auxiliary racks 17 and are guided by means of curved slots 23 provided at their ends and by rollers 24 and pins 8a of the racks 8 (Figure 1 left) in such a way that at a certain point of their vertical displacement they are displaced laterally. As can be readily seen from Figure 1 this lateral displacement of the guide rods 22 swings into the path of the toothed segments 13 the auxiliary racks 17 (attached to the rods 22) together with the rack levers 15 which are pivotally mounted on the pins 25 also attached to the racks 8, and engage in slots 21 in the guide rods 22 by means of rollers 26, whilst at the same time the levers 18, 18a release the impression cylinders.

The new control operates in the following manner. While the slide 2 is traversing the distance from A to B which corresponds to the length of the format of the printed matter, the rods 22 are pushed upwards in their curved guides in such a manner that shortly before B is reached the toothed segments 13 come into engagement with the racks 17 which at the commencement of engagement have the same velocity as the slide or nearly so. As soon as the engagement is effected the speed of the auxiliary racks in relation to the movement of the slide diminishes, and the cylinders accordingly begin to revolve.

Before the dead point C is reached the auxiliary racks 17 move backwards again, thereby imparting additional motion to the cylinders as far as the dead point C. In this way a length of paper web exceeding that of the format is drawn in at first but after the slide is reversed the racks 17 are moved further rearwards, until just before the impression begins, thus retarding the peripheral velocity of the impression cylinders by comparison with the velocity of the slide and thereby compensating the previous excess in the draft of the web. Shortly before the impression begins in the position in which the teeth of the auxiliary racks 17 are in line with those of the racks 8, the movement of the racks 17 ceases and the cylinders 1—the pinions 7 of which now gear with the racks 8—roll over the formes at a peripheral velocity equal to the speed of the slide.

In front of the dead point A, the toothed

segments 13 come into engagement with the rack levers 15, thereby causing the impression cylinders to revolve until the dead point A is reached and the channels are adjusted 5 parallel with the formes. The descent of the slide is accompanied by a downward movement of the guide rods 22, in such a manner that when the impression cylinders are at the dead point A the rack levers 15 are swung 10 out of the path of the toothed segments, whilst the simultaneous swinging of the check levers 18, 18a into action prevent the impression cylinders from turning.

The above described movement of the guide 15 rods 22 is transmitted thereto by the thrust member 27 through the articulated rods 16. The thrust member 27 which is guided on spindles 28 mounted on the frame of the press engages by means of a roller 29 in the 20 suitably designed cam groove 30 of a disc secured laterally on the crank wheel 3 and is thereby actuated.

The described movement of the auxiliary racks 17 can of course be effected in a different way without modifying the principle 25 of the invention. Thus given a suitable length and retardation in relation to the movement of the slide, the racks 17 could, for example be engaged at such a distance in front of the point B as to cause a length of paper equal to that of the format, to be drawn from the web during the movement of the slide up to the dead point C. In this case the auxiliary racks 17 are not moved during 30 the return movement of the slide so long as they are able to engage the toothed sectors 13. In such case the return of the racks 17 into their initial position takes place only during the impression or thereabouts.

40 For reasons of weight and in order to obtain minimum forces of acceleration, the impression cylinders may be constructed of aluminium or the like, whereas in view of rigidity of mounting, their journals are of 45 strong metal and for this purpose are provided with flanges which as shown particularly in Figure 4, overlap the cylinders and are bolted thereto.

I claim:—

50 1. In a printing press, having vertically disposed printing beds and having impression cylinders provided with channels and mounted in a rising and falling slide, a drive and control arrangement, comprising vertical racks mounted on the frame of the press, 55 pinions connected with the impression cylinders and engaging said vertical racks during the movement of the slide, a toothless gap on the periphery of each of said pinions corresponding to said channels on the impression cylinders, an auxiliary driving mechanism 60 for bridging over said gaps in the driving pinion and for initiating the rotation of the printing cylinders and means for bringing 65 said auxiliary driving mechanism into opera-

tion in such a manner, that the impression cylinders gradually are brought from a standstill to the full peripheral velocity.

2. In a printing press, having vertically disposed printing beds and having impression cylinders provided with channels and mounted in a rising and falling slide, a drive and control arrangement, comprising vertical racks mounted on the frame of the press, 70 pinions connected with the impression cylinders and engaging said vertical racks during the movement of the slide, a toothless gap on the periphery of each of said pinions corresponding to said channels on the impression cylinders, auxiliary toothed members 75 beside said pinions on the impression cylinders, positively controlled auxiliary racks adapted to be swung out of and into engagement with said auxiliary toothed members, and means for bringing said auxiliary racks into engagement with said toothed members and initiating the rotation of the impression cylinders in such a manner that the impression cylinders gradually are brought from a 80 standstill to the full peripheral velocity.

3. In a printing press, having vertically disposed printing beds and having impression cylinders provided with channels and mounted in a rising and falling slide, a drive and control arrangement, comprising vertical racks mounted on the frame of the press, 85 pinions connected with the impression cylinders and engaging said vertical racks during the movement of the slide, a toothless gap on the periphery of each of said pinions corresponding to said channels on the impression cylinders, auxiliary toothed members beside said pinions on the impression cylinders, positively controlled auxiliary racks adapted to be brought into engagement 90 with said auxiliary toothed members and initiate the rotation of said printing cylinders, and means for moving said auxiliary racks in the direction in which the slide is moved and for simultaneously swinging said auxiliary racks into the path of said toothed members in order to produce such engagement.

4. In a printing press, having vertically disposed printing beds and having impression cylinders provided with channels and mounted in a rising and falling slide, a drive and control arrangement, comprising vertical racks mounted on the frame of the press, 100 pinions connected with the impression cylinders and engaging said vertical racks during the movement of the slide, a toothless gap on the periphery of each of said pinions corresponding to said channels on the impression cylinders, auxiliary toothed members beside said pinions on the impression cylinders, positively controlled displaceable auxiliary 105 racks adapted to be brought into engagement with said auxiliary toothed members and initiate the rotation of said printing cylinders, and means for bringing said auxiliary racks into engagement with said toothed members in order to produce such engagement.

- inders, guide rods carrying said auxiliary racks, curved guide slots on the ends of said guide rods, guide rollers mounted on the frame of the press and cooperating with said 5 guide slots to swing the auxiliary racks into the path of the toothed members and means for reciprocating said guide rods and displacing the auxiliary racks in the direction of movement of the slide.
10. 5. In a printing press, having vertically disposed printing beds and having impression cylinders provided with channels and mounted in a rising and falling slide, a drive and control arrangement, comprising vertical racks, mounted on the frame of the press, pinions connected with the impression cylinders and engaging said vertical racks during the movement of the slide, a toothless gap on the periphery of each of said pinions corresponding to said channels on the impression cylinders, auxiliary toothed members beside said pinions on the impression cylinders, positively controlled displaceable auxiliary racks adapted to be brought into engagement with said auxiliary toothed members and initiate the rotation of said printing cylinders, and means including a cam slot in a disc coupled to the main drive of the press for reciprocating said guide rods and displacing the auxiliary racks in the direction of movement of the slide.
15. 20. 25. 30.

In testimony whereof I affix my signature.
FRITZ FALLERT.
